UNITED STATES PATENT OFFICE.

WILLIAM H. CAVER, OF BLUE MOUNTAIN, MISSISSIPPI.

FURNACE.

1,193,120.

Specification of Letters Patent.

Patented Aug. 1, 1916.

Application filed May 17, 1916. Serial No. 98,104.

To all whom it may concern:

Be it known that I, WILLIAM HOWARD CAVER, a citizen of the United States, residing at Blue Mountain, in the county of 5 Tippah and State of Mississippi, have invented a new and useful Furnace, of which the following is a specification.

The device forming the subject matter of this application is a furnace, adapted primarily but not exclusively for outdoor use.

The invention aims to provide a structure of this type which may be adjusted readily, to change its diameter, thereby adapting the furnace for pots, tanks and other vessels of 15 different diameters.

Another object of the invention is to provide novel means whereby the stack of the furnace may be used as a means for holding the furnace temporarily at an adjusted diameter, while the securing means of the furnace are being inserted.

It is within the province of the disclosure to improve generally and to enhance the utility of devices of that type to which the 25 present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings: Figure 1 shows in front elevation, a furnace constructed in accordance with the present invention; Fig. 2 shows the furnace in side 40 elevation; Fig. 3 is a transverse section of the furnace; and Fig. 4 is a fragmental perspective showing one end of the stack.

The furnace forming the subject matter of this application includes a drum 1 preferably made out of a sheet of resilient metal bent into circular form and embodying overlapped ends 2 and 3. The end 2 is provided adjacent its top and bottom with a plurality of openings 4. One or more openings 5 are 45 formed in the end 3 adjacent the upper and lower edges of said end. Securing devices 6 are mounted in the openings 5 of the end 3, and may be mounted selectively in any of the openings 4 in the end 2 in order to 50 vary the diameter of the drum 1. The securing devices 6 may be bolts,

The numeral 7 denotes a stack provided with a rectangular extension 8. In the rear of the drum 1 is fashioned an opening 9 in which the stack 7 is journaled. The stack 60 7 is provided with ears 10 which bear against the outer surface of the drum 1, and is provided with ears 11 bearing against the inner surface of the drum, the construction being such that the stack 7 is held for rotation on the drum. Fixed to and upstanding from the stack 7 is a finger 12. Mounted on the end 3 of the drum is a finger 14. The fingers 12 and 14 are united by a detachable connection 15, which may be a 65 piece of wire.

When the drum 1 is of considerable diameter, some difficulty is experienced in adjusting the drum, and in holding the drum in adjusted position while the bolts 6 are 70 being inserted. The extension 8 constitutes a lever whereby the stack 7 may be rotated on the drum 1, and when the stack thus is rotated, a pull is exerted on the connection 15. In this manner, the ends 2 and 3 of the 75 drum may be made to slip past each other for the purpose of bringing one of the openings in the end 3 into alignment with one of the openings 4 in the end 2, or for the purpose of holding such openings in alignment. After the openings are held aligned by the connection 15, the bolts 6 may be 80 inserted. The stack 7 and its extension 8 exercise a double function, since these elements serve at once to convey away the products of 85 combustion, and serve, as well, as a lever whereby the diameter of the drum 1 may be 90 adjusted, and whereby the drum 1 may be held at adjusted diameters.

At its front, the drum 1 is supplied with 95 a doorway 17. Secured to the drum 1 along the sides of the doorway are guides 18 in which is mounted to reciprocate, vertically, a door 19 having a finger piece 20, the construction being such that the door may be 100 raised readily to permit stoking. On the drum 1 may be placed a pot, tank or other utensil, indicated by the reference character 21.

In Fig. 3 of the drawings, the arrow A 105 indicates the direction in which the extension 8 of the stack 7 is turned, to secure a rotation of the stack. It is obvious that when the stack is rotated in the manner hereinbefore described, the connection 15 will be 110 tightened up to secure the results hereinbefore enumerated.

Having thus described the invention, what is claimed is:—

In a device of the class described, a drum having relatively movable ends provided with openings; securing devices mounted in the openings, the openings in one end of the drum being duplicated to permit an adjustment in the diameter of the drum; a stack journaled for rotation in the drum and provided with an extension whereby the stack may be rotated; and a flexible connec-

tion between the rotatable stack and that end of the drum which is remote from the portion of the drum wherein the stack is journaled.

In testimony that I claim the foregoing as my own, I have hereto affixed my signature in the presence of two witnesses.

WILLIAM H. CAVER.
